ADJUSTABLE HAT

Albert M. Broady, Pittsburgh, Pa.

Application November 24, 1942, Serial No. 466,787

4 Claims. (Cl. 2—197)

This invention relates to an improved hat for ladies' wear, and important objects and advantages thereof are to provide a hat of the character described, which is adjustable in size to conform to and accommodate the head of the wearer, which may be readily and conveniently adjusted by the wearer herself while same is positioned on the head, which embodies novel means for maintaining the hat in the adjusted position, which is simple in its construction and arrangement, attractive in appearance, and comparatively economical in its manufacture and use.

In the drawings, wherein like numerals of reference designate corresponding parts throughout the several views:

Figure 1 is a rear elevational view of an adjustable hat constructed in accordance with the invention.

Figure 2 is an enlarged, fragmentary rear view of the hat with portions thereof being shown in cross section.

Figure 3 is a front elevational view of the connecting link embodied in the present invention.

Figure 4 is a side elevational view of a modified form of hat structure.

Figure 5 is an enlarged, fragmentary, rear view thereof, with portions being in cross section.

Referring in detail to the drawings my improved hat comprises a crown 1 and a headband 2, which latter is secured to said crown 1. The headband is open, preferably but not essentially at its rear, to space respective ends 3 and 4 thereof in spaced relation to each other. A triangularly-shaped opening 5 is provided at the rear of the crown with the lower ends of the walls thereof being disposed at respective ends 3 and 4 of the headband 2.

A pair of similar adjusting straps, respectively indicated at 6 and 7, of considerable length, are permanently secured to respective ends 3 and 4 of the headband 2, by means of stitching 8, as shown, or in any other suitable manner. The adjusting straps are preferably reinforced by a plurality of rows of stitching 9 to prevent the stretching and distortion thereof when employed in adjusting operations.

A pair of holding loops, respectively indicated at 10 and 11, are secured at the outer side of the headband 2, and are disposed vertically at respective ends 3 and 4 of the latter.

The adjusting straps 6 and 7 are projected through a common connecting link 12 in the outward direction. The projected free end portion of the adjusting strap 6 is extended in one di-

rection through and engaged in the holding loop 10, and the projected free end portion of the adjusting strap 7 is extended in the opposite direction through and engaged in the holding loop 11, as clearly illustrated in Figure 1.

The connecting link 12 is oblong to conform to the width of the adjusting straps 6 and 7 passing therethrough. Preferably, the side members 13 of the connecting link are normally curved toward each other, as shown in Figure 3, to augment their gripping action on the adjustable straps 6 and 7, and thereby maintain the latter in the adjusted position. The acute flexure of the adjusting straps at the connecting link together with their insertion and engagement in respective holding loops in the manner above set forth, serve and further aid in maintaining the adjusting straps in the adjusted position. However, such flexure and engagement 10 of the adjusting straps in the connecting link 12 and holding loops 10 and 11, allows the slippage of said adjusting straps when a decided pull is exerted on the latter to effect their adjustment.

In adjusting the improved hat to reduce its size, it is only necessary to grasp the projecting free ends of the engaged adjusting straps 6 and 7 and pull the latter outwardly in opposite directions relatively to each other, whereby the ends 3 and 4, of the headband 2, will be drawn toward each other to reduce the circumference of the headband to conform to the head of the wearer. It will be apparent that such reduction adjustment may be readily and more properly effected by the user herself while the hat is positioned on the head.

The triangularly-shaped opening 5, provided in the hat crown 1 and opening into the space between the ends 3 and 4 of the headband 2, permits the contraction adjustment of the latter without appreciably distorting the designed contour of the crown 1. To increase the size of the headband 2, the adjusting operation is effected by exerting pull on the attached ends of the adjusting strands 6 and 7 to increase the distance between the ends 3 and 4 of the headband.

The adjusting straps 6 and 7 may be constructed of felt, fabric, or any other suitable material, and instead of being reinforced by the stitching 9 as shown, may be reinforced by embedded wires or any other suitable reinforcing material adaptable thereto. The holding loops 10 and 11 may be made of fabric, metal, or any other suitable material, and may be ornamental in design.

The modified form of hat, shown in Figures 4 and 5, comprises a brimless crown 14 having permanently attached at its bottom edge 15 and at one side thereof, a depending flap 16. A holding loop 17 is secured to the flap 16 and covers an oblong connecting link 19. A two-ply holding tab 18 is looped through the said link and projects upwardly from the latter a considerable distance above the holding loop 17. The covered end of the tab 18 is permanently secured to the flap 16 by stitching 20, whereby the link 19 is also secured in position beneath the holding loop 19.

A head strap 21 has one end thereof permanently attached to the side of the crown 14 opposed to the side of the crown carrying the flap 16. The other or free end portion 22 of the head strap 21 is looped downwardly through the connecting link 19 and is shiftably adjustable in the latter.

A button 23 is secured to the projected end of the strap portion 22, so that the latter cannot be inadvertently disengaged from the connecting link 19, as the latter is covered by the holding loop 17 rendering reengagement of the head strap with the connecting link extremely difficult. A similar button 24 is carried by the holding tab 18 to facilitate gripping the latter during adjusting operations.

The head strap 21 is adjusted by holding the tab 18 and exerting a pull on the downwardly projected end portion 22 of the head strap. The looped and flexed engagement of the head strap in the connecting link 19, together with the engagement of the holding loop 17, while allowing slippage for adjustment purposes, provides ample frictional resistance to maintain the head strap in the adjusted position.

With the foregoing description taken in connection with the accompanying drawings, the construction and method of operation of the invention will be readily apparent to those skilled in the art to which the invention appertains, and it will be understood that changes in the form, proportions, and details of construction may be

resorted to that come within the scope of the claims hereunto appended.

What I claim is:

1. In a hat, an adjustable open headband having the ends thereof disposed in spaced relation to each other, a pair of adjusting straps permanently attached to respective ends of said headband, a connecting element, said straps projecting through said element, and means carried by said headband for holding the projecting ends of said straps.

2. In a hat, an adjustable open headband having the ends thereof disposed in spaced relation to each other, a holding member carried at each end of said headband, a pair of adjusting straps permanently attached to respective ends of said headband, a connecting element, said straps being shiftably engaged in said element, and each of said straps being shiftably engaged in respective holding member.

3. In a hat, an adjustable open headband having the ends thereof disposed in spaced relation to each other, a holding loop carried at each end of said headband, a pair of adjusting straps permanently attached to respective ends of said headband, a connecting link, said straps being shiftably engaged in said link and having the free end portions thereof shiftably engaged in respective holding loops.

4. In a hat, the combination of an adjustable open headband having the ends thereof disposed in spaced relation to each other, a holding loop secured at each end of said headband, an adjusting strap permanently attached to each end of said headband and being reinforced, a connecting link, each of said straps extending through and being shiftably engaged in said link and further being extended through and shiftably engaged in the holding loop disposed at the attached end thereof, the engagement of said straps in said link and in said loops allowing the adjustment of said headband by a pull on said straps and normally maintaining the latter and said headband in the adjusted position.

ALBERT M. BROUDY.
